JONATHAN CRABTREE, OF PHILADELPHIA, PENNSYLVANIA, ASSIGNEE
TO JAMES BROMLEY & BROTHERS, OF SAME PLACE.

Design No. 4,305, dated August 30, 1870.

DESIGN FOR A CARPET PATTERN.

The Schedule referred to in these Letters Patent and making part of the same.

I, JONATHAN CRABTREE, of Philadelphia, county of Philadelphia, State of Pennsylvania, have invented and produced a Design for a Carpet Pattern, of which the following is a specification.

The accompanying drawings represent sufficient of carpet to illustrate my design, which consists of a series of square figures, A, each figure having, on each of its four sides, a border, recessed, as shown, and the border inclosing the foliated scroll, illustrated in the drawings.

The pattern also contains figures, a, of the form and arranged in respect to the larger figures, in the manner shown.

Irrespective of the colors employed—
I claim—

The design for a carpet pattern, substantially as described, and illustrated in and by the accompanying drawings.

In testimony whereof I have signed my name to this specification in the presence of two subscribing witnesses.

JONATHAN CRABTREE.
